UNITED STATES PATENT OFFICE.

WILLIAM H. MILLER, OF CANTON, OHIO.

HOT-WATER BOTTLE.

1,372,893.

Specification of Letters Patent. Patented Mar. 29, 1921.

Application filed December 16, 1918. Serial No. 266,988.

To all whom it may concern:

Be it known that I, WILLIAM H. MILLER, a citizen of the United States, residing at Canton, in the county of Stark and State 5 of Ohio, have invented a new and useful Hot-Water Bottle, of which the following is a specification.

This invention relates to hot water bottles, the object being to construct a hot 10 water bottle with interior partition walls formed integral with the two sides of the said bottle to prevent the bottle from bulging in the center when filled with water.

Another object is to prevent all of the 15 water in the bottle from running to one side if the bottle is only partially full.

Another object is to prevent the sides of the bag from adhering one to the other when the water is drained out and the said 20 bag is not in use.

With these objects in view the invention consists in the novel construction and arrangement of parts, hereinafter described, illustrated in the accompanying drawings, 25 and particularly pointed out in the appended claims, it being understood that various changes in the form, proportions, size and minor details of construction may be made within the scope of the appended claims, 30 without departing from the spirit or sacrificing any of the advantages of the invention.

In the drawings:

Figure 1 is a side elevation of a bag constructed in accordance with my invention 35 with the partition walls shown in dotted lines.

Fig. 2 is a section on line 2—2 of Fig. 1.

Similar numerals of reference indicate 40 corresponding parts throughout the several figures of the drawings.

Water bottles of ordinary construction when filled to capacity, will be greatly inflated at the center, thus describing a broad 45 ellipse in cross section. It is obvious that such a bag will have a tendency to roll and will not lie in position when placed upon a part of the body. On the other hand if the bag is only partially filled with water if 50 laid upon a rounding portion of the body, such as one of the limbs, all of the water seeking the lowest level will flow to one side of the bottle and again prevent the bottle from lying in position. Again it is found 55 that when the ordinary type of bottle has

been emptied and is not in use for a brief length of time the rubber sides will stick together and make it a difficult matter to refill the bottle in order to use it.

In order to obviate these objections I construct my bottle shown at 1 in the drawings with a plurality of partition walls 2, which partition walls preferably do not extend the entire length of the said bottle, a space being left between one extremity of the partitions and the interior wall of the bottle to allow the water to enter and fill all the compartments. A bottle so constructed when entirely filled with water will be no wider at the center section 3 than at the side sections 4 and 5, the result being that the bottle is substantially flat in general contour, as clearly indicated in Fig. 2.

Attention is directed to the fact that the partition walls 2 extend to the lower end 75 of the bottle and their extremities connected to the bottom of the bottle, whereby the lower ends of the three compartments 3, 4 and 5 are closed against communication with each other, while their upper ends are 80 located below the top of the bottle and are in communication with each other and common to the filling mouth of the bottle. By reason of this construction, the amount of water in the bottle can be substantially 85 equally proportioned in the several compartments by a manipulation of the bottle with its filling opening closed, or a greater amount may be maintained in either of the pockets when it is desired to unequally ap- 90 portion a relatively small amount of water between the several pockets.

Attention is also directed to the fact that the partition walls 2 have a width narrower than the extended cross-sectional area of the 95 pockets of the bottle, as shown in Fig. 2, whereby the bottle maintains a ribbed or corrugated exterior surface as also shown in Fig. 2. By reason of this construction the bottle has a clinging tendency to the body 100 of the person and is prevented from sliding sidewise as it would do if its exterior surface were not ribbed or corrugated.

It will be readily seen that a bottle so constructed when filled with water will 105 form a flat pad which will not slide nor roll and will thus remain in position when placed upon any part of the body.

It will also be obvious that the partition walls 2 will prevent the side walls from 110

coming in contact with each other and thus preclude the possibility of their adhering when the bottle is empty.

Having fully described my invention 5 what I claim as new and desire to secure by Letters Patent, is—

1. A hot water bottle having a plurality of longitudinally extending spaced partitions having their edges connected to the 10 inner wall of the bottle, said partitions having a width less than the cross-sectional extended area of the bottle between the partitions, whereby the exterior surface of the bottle when filled with liquid has longitudinal 15 corrugations for the purpose described.

2. A hot water bottle having a filling mouth and longitudinally extending partitions therein, the edges and lower ends of the partitions connected throughout to the 20 inner wall of the bottle with their upper ends ending below the upper end of the bot-

tle whereby the bottle is provided with a plurality of longitudinally extended pockets having closed sides and the lower ends and open upper ends communicating with the 25 filling mouth of the bottle.

3. A hot water bottle having at one end a filling mouth, a plurality of longitudinally extending partitions of less width than the extended width of the bottle between the partitions, the edges and lower ends of the partitions united to the inner wall of the bottle throughout the partitions and their upper ends ending below the filling mouth of the bottle, whereby the bottle when filled has corrugated outer surfaces and pockets which are out of communication with each other at their bottom, combined for the purpose described.

In testimony that I claim the above, I 40 have hereunto subscribed my name.

WILLIAM H. MILLER.
